DESIGN FOR A VALVE

William A. Ray, Glendale, Calif., assignor to General Controls Co., a corporation of California

Application November 4, 1938, Serial No. 80,879

Term of patent 14 years

To all whom it may concern:

Be it known that I, William A. Ray, a citizen of the United States, residing at Glendale, in the county of Los Angeles and State of California, have invented a new, original, and ornamental Design for a Valve, of which the following is a specification, reference being had to the accompanying drawing, forming part thereof.

The figure is a perspective view of a valve embodying my new design.

The side of the valve not shown in the drawing is substantially the same as the side shown.

I claim:

The ornamental design for a valve, substantially as shown and described.

WILLIAM A. RAY.
